CLAIM

The ornamental design for a cooler, as shown and described.

DESCRIPTION

FIG. 1 is a top, front, right perspective view of a cooler showing our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The broken lines and the unshaded areas within them illustrate portions of the cooler and form no the claimed design. The cooler is shown with a symbolic break in its length. The appearance of any portion of the article between the break lines forms no part of the claimed design.
